UNITED STATES PATENT OFFICE.

CHARLES A. GRAY, OF KANSAS CITY, AND FREDERICK H. FARRAR, OF
NORTH ROSEDALE, KANSAS.

LIQUID-METER.

SPECIFICATION forming part of Letters Patent No. 628,312, dated July 4, 1899.

Application filed March 4, 1898. Serial No. 672,621. (No model.)

To all whom it may concern:

Be it known that we, CHARLES A. GRAY, residing at Kansas City, and FREDERICK H. FARRAR, residing at North Rosedale, in the county of Wyandotte and State of Kansas, citizens of the United States, have invented certain new and useful Improvements in Liquid-Meters; and we do hereby declare that the following is a full, clear, and exact description of the invention, such as will enable others to make and use the same, reference being had to the accompanying drawings, forming a part of this specification.

The object of our invention is a safeguard in the dispensing of liquids in fractional quantities from the liquid in bulk, so that the exact amount withdrawn at any one time from the tank will be accurately registered, as well as each partial withdrawal and subsequent replenishing of liquid in a standard liquid-measure.

Our invention furthermore is designed for the detection of waste and unauthorized withdrawals in amount of all kinds of liquids in bulk; and it consists in the novel construction and arrangement of devices hereinafter more fully described, and specifically pointed out in the claims.

In the drawings, Figure 1 is a view in perspective of a broken rear end portion of the reservoir or tank containing the liquid in bulk and of the novel liquid-meter connected therewith for receiving measured quantities of liquid with a portion of the upper case broken away to show the automatic registering mechanism. Fig. 2 is a vertical sectional view of the three-way cock. Fig. 3 is a rear view in detail of the lower end portion of the separate winding-rollers for the scale-sheet and also of the stationary rods and back plate for the scale-sheet and showing a portion of the top of the measuring vessel. Fig. 4 is a detail view of a broken portion of the ratchet-wheel on the lower end of the winding-roller for the movable scale-sheet, showing the end of the horizontal bar and pawl actuating the said wheel. Fig. 5 is a view in detail of the slotted tube opposite the scale-sheet, showing the spiral spring, the pencil and pin, also showing the guide-plates on the guide-rods in vertical section.

Similar letters of reference indicate corresponding parts in all the figures.

Referring to the drawings, A in Fig. 1 represents a reservoir or tank for the convenient storage of a large quantity of liquid and is mounted upon a support or bed B.

a is the discharging-end portion of tank A.

Upon the under side of tank A and connected therewith is a bracket a', the forward edge portion of which bracket is nearly in line with the end a of said tank A. Near one end a of tank A is a standard liquid measure or vessel C, which, as illustrated, is cylindrical in form, the upper portion of the side of which is connected with the bracket a' on the under side of tank A, the upper end of the said measuring vessel extending upwardly to a position near the lower part of the end a of tank A. 70

c represents the bottom of vessel C, and c' the top or cover, which, for the purpose of hermetically sealing the top and preventing the escape of any liquid in that direction, is secured to the vessel A in the following manner: Near the upper circular edge portion of the vessel C is a shoulder c², extending entirely around the outer side of the vessel, and from the inner side of the shoulder is an upwardly-extended annular flange c³, which forms the upper edge of the vessel C. The cover c' consists of a circular flat plate, on the outer edge portion of which is a downwardly-extended flange c⁴, which extends over the annular flange c³ and contacts with the shoulder c², which shoulder c² and flange c³ are soldered together or otherwise hermetically connected. On the upper surface of the top c' and a short distance from the outer edge is an upwardly-extended annular flange c⁵ for 90 retaining the case hereinafter described in position.

With the under side portion of the tank A upon one edge of the bracket a' is connected one end of a fluid-conducting pipe D, the other end of which pipe extends downwardly to a position a short distance below the line of the under side of bottom c of the measuring vessel C and is bent at right angles and extended in a horizontal direction and forwardly beneath the bottom c of said vessel to a position a short distance beyond the

vertical plane of the front portion of said vessel C and is connected directly beneath the central portion of the bottom c with the inlet e of an ordinary three-way valve E, through which extends transversely the valve-stem e', and upon the other end of which stem is a lever e². With the outlet e³ of the valve E is connected one end of a short discharge-pipe d', the other end of which pipe extends 10 a short distance beyond the vertical plane of the front side of the vessel C and terminates in a downwardly-bent portion d². With the opening e⁴ in the upper side of the valve E is connected one end of a short piece of pipe d³, 15 the other end of which pipe is connected with the induction-opening c^x in bottom c of the vessel C.

Upon the upper surface of the top c' and upon the portion of said top, near the end a of tank A, are separate vertical sheet-winding rollers F F', which are arranged in position a short distance apart and upon a line parallel with said end a of tank A. Upon the lower end of the roller F is a pivot f, which enters 20 a slight depression f' in the upper surface of the top or cover c' of the vessel. Upon the lower end of roller F is fixed an annular collar f², extending around the upper horizontal edge portion of which are ratchet-teeth f³. 25 Upon the lower end of the roller F' is a pivot f⁴, which enters a slight depression f⁵ in the top c' of the vessel C. The rollers F F' are of the same height and both extend a considerable distance vertically above the top c' of 30 the vessel C to permit of a proportional scale-sheet to be arranged in position thereon in ratio with the cubical contents of the measuring vessel C. On the upper end of each one of the rollers F F' is a pivot f⁶.

Extending through the surface of the top c' of the vessel C, at a point on said top equidistant from the vertical flange c⁵ of the top c', is a stuffing-box g. On each side of the stuffing-box g and parallel in position with a line extending horizontally through both rollers F F' are separate stationary guide-rods G G', secured at their lower ends to the upper surface of the top c' of the vessel C and extending in a vertical direction the same described height of the rollers F F'. Directly opposite the rods G G', in the direction of the end a of tank A and a slight distance toward said rods G G' in advance of a line extending horizontally through the rollers F F', are separate stationary rods H H', which are connected rigidly at their lower ends with the top c' of the vessel C at a short distance, respectively, from the rollers F F', the upper ends of which rods extend vertically to the described height of the stationary guide-rods G G'. With the upper end portions of the separate rods G G' is connected a flat plate I, which is perforated at i to receive the said end of said rods. The other end of plate I 65 extends to a position directly above the upper screw-threaded ends of rods H H' and are also perforated to receive the upper ends of

said rods H H', and upon said screw-threaded ends is a nut i². At the end portion of plate I, which is connected with the upper end of rod H, and upon one side of said plate is a curved extension i³, which receives the pivot f⁶ on the upper end of the roller F and supports said roller in position. Upon the other side of plate I is a curved extension i⁴, which 75 extends to a position above the upper end of roller F' and is perforated to receive the pivot f⁶ on said roller.

Directly in front of the rods H H' is an outwardly-curved plate K, which extends from the upper surface of the top c' to the under side portion of the plate I. One vertical edge portion of plate I is bent rearwardly and extended around the stationary rod H, and the other edge portion is bent rearwardly and extended around rod H'. On the stationary guide-rods G G' are the separate vertically-movable guide-plates L L', which are arranged a short distance apart. On the guide-rod G, between said plates L L', is a sleeve l, the upper end portion of which is secured rigidly to the under side portion of plate L and the other end with the upper side portion of the plate L'. On the guide-rod G', between the plates L L', is a sleeve l', which is secured to said plates, as described of sleeve l, thus giving a 90 steadiness of movement to said plates L L'.

Through both plates L L', at a point equidistant from rods G G', extends the upper end portion of a movable float-valve stem or rod m, upon which and above the plate L is an adjustable collar m', in the side of which collar is an adjustable screw m². On the under side of the plate L is an adjustable collar m³, in the side of which is an adjustable screw m⁴. The other end of the valve-stem m extends downwardly through the stuffing-box g and is connected with the float-valve M as follows: The float-valve M consists of a hollow air-tight case, circular in form and composed of top m⁵ and a bottom m⁶, both of which extend in the same horizontal plane from near the inner portion of one side of the vessel C nearly to the other side of said vessel, so as to move freely without frictional contact the inner side of said vessel. The plates m⁵ m⁶ are arranged a short distance apart for buoyancy and are rigidly connected at the outer edge with the annular plate m⁷, which forms the side to said float-valve. 110

Through the center of the top m⁵ of the float-valve, at a point equidistant from the annular side m⁷, is extended one end of a tube m⁸, which tube extends to the under side portion of the bottom m⁶ and is here hermetically sealed in the valve. In tube m⁸ is inserted the lower end of the valve-stem m and secured, by soldering or otherwise, fixedly thereto. In order to relieve the valve-stem from any inclination induced by the liquid and also 120 guide its movements, a guide-rod N is secured rigidly to the under side portion of the top c' of the vessel C at a point a short distance from the inner portion and one side of vessel

C and the other end extended downwardly through a tube m^9 , in line therewith in the float-valve M, which is similar to the tube m^8 in the center of the float-valve, and the other 5 end of said rod connected by soldering with the inner side of the bottom c of vessel C, the circumference of rod N being slightly less than the dimensions of the tube m^9 . Near the other side of the vessel C and connected with 10 the inner side of the top c is a vertical guide-rod N', which extends downwardly through the tube m^9 , connected with the valve-case M in precisely the same manner as described of the guide-rod N, the lower end of which 15 rod being connected with the inner side of the bottom c of vessel C.

With roller F is connected in any preferred manner one end of the scale-sheet P, which consists of a sheet of paper or other flexible 20 material, which will in this instance be wound upon the rollers F F', and of the proper length. The said sheet P extends in height from a point on roller F a short distance above the ratchet-teeth f^3 on the collar f^2 upwardly 25 nearly to a point in line with the under side portion of the plate I. One end of the sheet P is secured by glue or other means to the roller F and the other end is extended over the outer curved surface of plate K and is 30 wound a number of times upon roller F' and secured to the said roller in any well-known manner.

On the face of the sheet P and upon the end portion connected with roller F is a scale p, 35 beginning with the "0" mark near the lower edge of the sheet O and in an ascending series, consisting of the numerals "1," "2," "3," "4," and "5," which are arranged as follows: From the "0" mark at the foot of the scale 40 p and in line opposite said "0" in an upward direction are four separate additional horizontal lines at equal distances apart one from the other, and extending the entire length of sheet P and opposite the fourth line from the 45 "0" is a numeral "1," between which numeral and the "0" a distance is described indicative of a certain defined amount of liquid admitted to the measuring vessel C from tank A, as will be hereinafter described, and between 50 each line a space, each space being indicative of the separate defined divisions of the total quantity of liquid inducted between the "0" and the numeral "1."

At the same described distance upwardly 55 on sheet P from the line indicated by the numeral "1," as described, between said numeral and the "0" mark, is a horizontal line indicated by the numeral "2," and between said lines are separate lines and spaces at 60 the precise distance apart, as between the heretofore-described lines between those indicated by the "0" mark and the numeral "1." The series of spaces respectively indicated by the numerals "3," "4," and "5" 65 are one above another and in exact correspondence with the other spaces described.

With the inner edge portion of the plate L'

in the direction of the sheet P is rigidly connected one end of a tube R, the other end of which tube extends in the direction of and 70 about two-thirds the described distance from said plate L' to the scale-sheet P, in the side of which tube is a longitudinal slot r. In the tube R is a lead-pencil r', in the side of which pencil is a pin r'', extending through the slot 75 r. Within the tube R in rear of the inner end of pencil is a coiled spring r'', the outer end of which pencil is in contact with the scale-sheet P and retained in said position by the spring r''. Upon one side of the tube r 80 and nearly opposite the roller F is a block S, which is secured to the top c' of the vessel C, and with the side of which block is rigidly connected one end of a flat spring S', the other 85 end of which spring bears upon the scale-sheet P on roller F' with slight tension and retards the unfolding thereof. Upon the other side of the tube R and near the roller F is a guide-block t, which is secured to the top c' of the vessel C, and through the opening t' 90 in which is extended one end of a reciprocating bar T, which extends to a position on the inner side of the roller F and directly above the ratchet-teeth f^3 on the collar f^2 , and upon the sides of which bar are separate 95 downwardly-extended lugs t' t'', and between said lugs is a pawl t'', having a pivot t' extending transversely through said lugs. The other end of bar T extends horizontally in the direction of the front side of the vessel C 100 and a short distance beyond the outer edge portion of said top c'. Upon the front vertical side portion of the vessel C, on opposite sides of a vertical line extending through the outer end of bar T, are separate outwardly- 105 extended guide-plates u u, between which is pivoted at a point u', which is nearly equidistant from the top c' to the bottom c of the vessel C, an oscillating lever U, the upper end of which lever is pivotally connected with the 110 outer end portion of the sliding bar T and lower end extended downwardly to a position upon the side of the pipe d', having the handle e', to the three-way cock E. Upon the valve-rod e' to said cock is a fixed eccentric- 115 plate v, around which is extended a ring v' and with which ring is connected one end of an eccentric-rod v'', the other end of which rod is pivotally connected with the lower end of the oscillating lever U. The oscillating 120 lever U is covered or concealed the greater part of the length by the front plate u' on the guide-plates u u. On the top c' of the vessel C, near the roller F, is fixedly connected one end of a flat spring u'', the other 125 end of which spring bears upon the ratchet-teeth f^3 of the collar f^2 on the roller F and regulates the movement of the roller F when actuated by the pawl t''. For the purpose of concealing all of the exposed parts of the meter a circular case W of the same circumference as that of the vessel C is placed upon the top c' of the said vessel and having a top w 130 extending above the rollers F F', the lower

edges of the sides of which covering-case W extend on the other side of the flange c^5 of the said top.

With the top portion of the tank A is connected one end of an air-pipe X, the other end of which pipe extends to a position above the top w of the case W, and thence bent at an angle, as at x , and extended downwardly near the front portion of the vessel C and connected with the top portion c' of said vessel.

On the outer side portion of the case W and near the lower edge portion is a hasp Y, and on the side of the vessel C is a staple y' , over which the hasp passes and is secured by padlock y' . Other hasps Y and staples are secured to the case W and vessel C at suitable points in the direction of the circumference of the said vessel and case in like manner as the hasp Y.

In the employment of the improved meter, as hereinafter described for its intended use, the float-valve M before the introduction of the fluid is at the bottom of the vessel C, and likewise the registering devices are at the lowest position, with the end of the pencil r' upon the lowest line upon the scale-sheet P and opposite the "0" mark upon said sheet, this adjustment of the pencil being readily effected by the movement of the guides L L' on the valve-stem m , for which purpose the collars $m' m^3$ are released by the set-screws $m^2 m^4$ and the proper adjustment of the guides L L' then made. The tank A, it will be observed, which for the purpose of retailing may or may not have an exact, but an approximate, known quantity, is filled with the liquid to its full capacity and is admitted first to the vessel C. For the purpose of admitting the liquid to the vessel C the lever e^2 is thrown from a position as seen in dotted lines into the position as seen in full lines in Fig. 1, and the draft is made upon the liquid in the tank A. The can or other vessel into which the liquid is drawn is placed beneath the bent portion d^2 of the discharge-pipe d' . The liquid thus admitted through valve E enters the vessel C, beneath the float-valve M, through the pipe d^3 , and the float-valve, whose buoyancy retains a position upon the surface of the fluid, rises with the inflowing liquid and is guided by the guide-rods N N', the air above the valve passing up the pipe X into the tank A. In order, therefore, to fill the vessel C and carry the float-valve to the top c' of the vessel, said vessel C is made of a certain standard, and for illustration suppose the cubic contents of the vessel C when the float-valve M is at its highest elevation will be equal to five gallons exactly of the liquid, and as liquids vary in density let the liquid be the ordinary refined burning fluid commonly called "coal-oil." It will then be perceived that the scale from "0" to "5" will indicate the cubical contents of the refined oil in the vessel C, and, furthermore, that so much in quantity less than five gallons to that of one quart or even less the circumference of the vessel C is of

such dimensions that, the amount of liquid at each level being absolutely defined in the measure C, the scale-sheet P becomes an automatic index of the graduated amounts less those five gallons admitted to the said vessel C. In proportion to the increased size of the measure C of course must follow an increase in the size of the scale-sheet P. Suppose, then, that the usual amount at one delivery from tank A would require an amount equal to the capacity of the tank C. The pencil r' being upon the lowest point of the scale-sheet P at the "0" mark, as heretofore stated, the rearward movement of the lever e^2 causes the eccentric $v v'$ and rod r^2 to actuate the pawl t^3 and turn the roller F one degree, and consequently move the scale-sheet a proportional distance toward the collar F, past the pencil-point r' , thus leaving a mark on the scale-sheet, and in the same movement of lever e^2 the liquid enters the vessel C, and the valve-stem m and float-valve M move upwardly, and with them the guides L L' and the pencil r' , the said pencil making a mark on the scale-sheet on a straight line to the top of the scale-sheet and opposite the line following the numeral "5". As soon as the vessel is filled with the liquid the lever e^2 is given a quarter-turn to a vertical position, as seen in dotted line, which closes the valve in the direction of the tank A and permits the contents of the vessel C to be discharged through the pipe d' . In this movement of the valve e^2 the lower end of the oscillating lever U is forced outwardly, causing the pawl t^3 on the ratchet-teeth f^3 to pass over the ratchet-teeth and engage with a ratchet-tooth in advance. As the float-valve moves downwardly the pencil also moves downwardly on the same line made going up and continues also to indicate the full discharge of the liquid from the measuring vessel C. Suppose, however, that instead of withdrawing the full amount of liquid from the vessel C one or two gallons of the liquid are taken from the vessel C and no more. The valve-lever e^2 being given a quarter-turn to stop the flow of the liquid, the pencil r' stops on the scale-sheet at the proportionate distance downward from the top of the scale-sheet. The pawl t^3 causes the roller F to move the scale-sheet one degree, the pencil describing a horizontal line on the scale-sheet from the vertical line, and the valve E being open toward the supply-pipe D the liquid flows into the vessel C and the float-valve moves upwardly to the top of the tank, the pencil r' indicating the exact distance traversed on the scale-sheet upwardly and the amount required to refill the vessel C. In order, therefore, to obtain the liquid from tank A, the vessel C must contain an amount to be drawn upon, and while the lever e^2 is turned so as to prevent the discharge from the pipe d' the liquid is passing from tank A into the vessel C and continues until the float-valve receives the highest elevation, when the flow stops of itself, the amount,

however, being indicated in each instance upon the scale-sheet, so that whatever fractional quantity of liquid may be taken from the vessel C it will be accurately recorded, and 5 the marks upon the scale-sheet when the tank A is empty will be a permanent record of the quantity originally in the tank and of the successive amounts drawn and its exact measure, as well as indicating the number of times 10 the valve E is operated and the amounts discharged between the opening and closing of the said valves. The scale may be arranged to indicate the smaller standard measures less than one gallon, so that in wine measure the 15 adjustment of the scale may be varied to the proportionate capacity of the wine-measuring vessel.

The meter may be made of various proportions and the supply-pipe connected directly 20 with a water-service pipe when required. The scale-sheet P may be replaced by others of the same design and size when the occasion requires.

When pressure is used on the liquid in the 25 measuring vessel, the air-vent pipe X may terminate within the vessel W or the air relieved around the valve-rod, the upper part of the float-valve at its highest elevation closing the space around the stuffing-box and 30 preventing the escape of the liquid.

Having fully described our invention, what we now claim as new, and desire to secure by Letters Patent, is—

1. In a liquid-meter the combination with 35 a hermetically-sealed liquid-measuring vessel, of a float-valve therein, and a valve-rod extending through the top of said vessel, a cut-off valve beneath the bottom of said vessel, having separate three-way openings, and 40 a valve-stem, a pipe leading from one of said valve-openings to the bottom of said measuring vessel, and a separate pipe leading from said valve to the source of supply for the liquid, and a discharge-pipe for the liquid ex-

tending from said valve, separate pivoted 45 sheet-carrying rollers upon the top of the measuring vessel, and a detachable sheet having a scale indicating the amount within and drawn from the measuring vessel upon said sheet, a collar upon the lower end of one 50 of said rollers and ratchet-teeth upon said collar, and a horizontal reciprocating bar in suitable guides upon the top of said vessel, and a pawl upon said bar engaging with said ratchet-teeth, a pivoted oscillating lever on 55 the forward part of said measuring vessel, connected at its upper end with said horizontal bar, an eccentric on the valve-stem, and an eccentric-rod connected with the lower end of the oscillating lever, and adjustable 60 recording devices on the upper end of the valve-rod to the float-valve, in contact with the movable scale-sheet.

2. The combination with a tank for liquids in bulk of a hermetically-sealed liquid-measuring vessel a liquid-supply pipe connected with the said tank and also with the bottom portion of said measuring vessel and an air-vent to said vessel, a float-valve within said measuring vessel a valve-rod extending 70 through the top of the said vessel, a movable sheet having a scale thereon indicating the amount of liquid admitted to and drawn from the said vessel, endless traveling carriers of said scale-sheet upon said measuring vessel, 75 a motor for actuating said carriers upon said measuring vessel, recording devices upon the top of said measuring vessel movably connected with and actuated by the valve-rod to the float-valve in contact with the said scale-sheet and suitable fixed guides upon said measuring vessel for said recording devices. 80
